MICROPHONE AMPLIFIER

Alfred J. Mastropole, New York, N. Y., assignor to
 Sonotone Corporation, Elmsford, N. Y., a corporation of New York

Application August 3, 1940, Serial No. 350,245

6 Claims. (Cl. 179—107)

This invention relates to microphone amplifiers for hearing aids and it has among its objects an improved wearable microphone amplifier which is so combined with the microphone, battery and receiver of the wearable hearing aid as to permit quick change-over from amplified operation with the amplifier operatively connected between the receiver and the microphone, to simplified operation with the receiver directly connected to the microphone, without changing the operative correlation of the terminals interconnecting the microphone, the receiver, the battery and the cord.

The foregoing and other objects of the invention will be best understood from the following description of exemplifications thereof, reference being had to the accompanying drawings wherein

Fig. 1 is a vertical cross-sectional view along line 1—1 of Figs. 2 and 3 illustrating a hearing aid microphone amplifier exemplifying one form of the invention;

Fig. 2 is a cross-sectional view along line 2—2 of Fig. 1;

Fig. 3 is a cross-sectional view along line 3—3 of Fig. 1;

Fig. 4 is a cross-sectional view along line 4—4 of Fig. 3;

Fig. 5 is a bottom view of the amplifier shown in Figs. 1 and 2, parts being broken away to show the interior elements thereof;

Fig. 6 is a diagrammatic partially exploded view illustrating the mechanical as well as the electrical relationship of the elements of the amplifier and the cooperating parts of a wearable hearing aid; and

Fig. 7 is a view similar to Fig. 6 illustrating another exemplification of the invention.

A typical wearable microphone amplifier hearing aid the general arrangement of which is shown in the diagram of Fig. 6 usually consists of a microphone 10, a control unit 11, a hearing inducing receiver 12, a microphone amplifier unit 13 having an actuating winding 14 and an amplifier microphone 15, which are energized by a battery 16 and are interconnected by a cord 17, which usually has a detachable plug 18 for connecting it to the amplifier unit, the battery being usually connected to the circuit through two battery plugs 21, 22 extending from the microphone amplifier casing and engaging terminal sleeves 19 of the battery.

When the microphone amplifier is connected in the circuit, the control unit 11, which is usually housed together with the microphone 10 in a small flat casing, completes a connection from

the positive battery terminal 19, through the amplifier battery terminal 21, by way of a terminal member 23 of the amplifier unit, to a lead of the cord 17, and a slider contact of the control unit 11 to one electrode of the microphone, and back from the other microphone electrode, through a cord lead to the amplifier cord terminal 24, and therefrom by way of a suitable lead 25 in the amplifier to one end of the amplifier actuating coil 14, the other end of which is connected through a lead 26 to the other amplifier battery terminal 22, which engages the battery terminal of opposite polarity; the output circuit of the amplifier being at the same time completed from the positive battery supply terminal 19, through the previously traced connection to the slider contact of the control unit 11, and therefrom over the rheostat of the control unit, the cord lead including windings of the receiver 12 to the amplifier cord terminal 21, and therefrom through the connections including the amplifier lead 28 to one electrode of the amplifier microphone, the other electrode of which is connected through lead 26 to the amplifier battery terminal 22 which engages the negative terminal of the battery 16.

When the control unit 11 is in the position shown, the microphone 10 is thus connected in series with the amplifier winding 14 for actuating the amplifier microphone 15 with modulated speech frequency input currents, and the rheostat of the control unit connects the battery in series with the receiver 12 and the amplifier microphone 15 for actuating the receiver with amplified output currents.

Such amplifier microphone is usually housed in a casing having a bottom wall held on the top of the battery 16 by its two terminal plugs 21, 22, which engage the terminal sleeves of the battery so as to form a mechanical as well as an electrical connection between the amplifier unit and the battery and join them into a single unit which may be conveniently hidden in a pocket of the user.

In accordance with the invention, the part of the microphone amplifier unit in which are anchored the terminal members through which the connection to the battery is made and the part of the amplifier unit in which are anchored the terminals through which the connections to the cord circuit are made, are arranged in the form of two switch members which are relatively movable between one position in which the two switch members interconnect the microphone amplifier between the microphone and the receiver and

another position in which the receiver is directly connected to the microphone.

Figs. 1 to 5 illustrate the structural features of one form of such microphone amplifier, Fig. 6 illustrating diagrammatically in an exploded perspective view the functional relationship of the switching elements of the amplifier unit. The casing of the amplifier unit has a bottom wall 31 made, for instance, of a synthetic resin molding, and having at one end a terminal block in which are embedded the three terminal bushings 23, 24, 27, as in the usual microphone amplifiers, a housing cover 32 being suitably secured, as by screws, to ledges 33 extending along the edges of the base plate to complete the housing.

On a suitable upwardly projecting bracket arm 35 extending, for instance, from a contact plate 36 embedded in the molded bottom wall 31 is secured the microphone amplifier assembly which may be constructed, for instance, in the way described in the copending application Serial No. 328,336, filed April 6, 1940. The anchoring element 36 of the supporting bracket 35 has an extension which serves as a contact strip 41 which, together with similar cooperating contact strips 42, 43, 44, 45, are secured, as by molding, within the bottom wall 31 so as to expose their outer contact surfaces flush with the surface of the bottom wall, to the interior of the amplifier housing.

The contact surfaces 41 to 45 are arranged to slidably cooperate with contact pins 51, 52, 53, 54 mounted at the ends of contact spring arms 55, 56, 57 suitably secured to a mounting plate 58 slidably held on the upwardly facing surface of the amplifier bottom wall 31. The mounting plate 58 for the contacts 51 to 54 is slidably held in position above the bottom wall 31 by the rivet heads of three internally threaded bushings 61, 62, 63 extending through suitable guide slots 61', 62', 63' of the bottom wall 31, and clamped to a similar mounting plate 64 slidably fitting within a recess 65 formed on the outer side of the bottom wall 31, threaded studs of the two battery plugs 21, 22 and an additional screw 66 engaging the inwardly threaded surface of the three bushing rivets 61, 62, 63 so as to hold the two mounting plates 58 and 64 slidably clamped to the opposite sides of the central portion of the bottom wall 31 and to permit slidable movement of the switching contacts 51 to 54 of the mounting plate 58 relatively to the switching contacts 42 to 45 of the bottom wall to establish in the position shown the amplifier interconnections, and in the other position a direct operating connection between the microphone and the receiver.

The amplifier unit has its actuating winding 14 and its amplifier microphone interconnected between the contact plates 41, 44, 45 of the bottom wall so that when the contacts 51 to 54 which carry the battery terminals are in the position shown in the drawings, the amplifier is connected between the microphone and the receiver, and that when the contacts associated with the battery terminals 21, 22 are in the dotted-line positions indicated in Fig. 6, the microphone 10 is connected directly with the receiver under the elimination of the amplifier, the amplifier being cut out from the operating circuit.

The casing wall portions 64, 58 to which the battery terminal plugs 61, 62 are secured is biased to either one or the other switching positions by a toggle spring 71 formed of a wire having two spring arms confined in a shallow depression 72 in the inner wall surface of the recess 65 in which

the wall portion 64 is slidably movable. The two arms of spring 71 have ends 73, 74 bent outwardly in opposite direction and engaging holes 73', 74' in the slideable wall portion 64 and the facing wall 5 of the recess depression 72 so that if the base plate 31 of the casing is moved relatively to the casing wall portion 64 which is anchored in the top of the battery, the snap action of the toggle spring 71 brings the switch contacts to the other position, as soon as the two spring ends 73, 74 are moved past their unstable equilibrium center.

Fig. 7 illustrates a modified amplifier arrangement of the invention, in which the elements of the switch mechanism are combined in a self-supporting switch unit suitable for plugging into the socket sleeves 19 of the battery unit, the switch unit being provided with socket sleeves 81, 82 into which a distinct amplifier unit 80 is plugged in. The switch unit has a bottom wall 31 with 20 battery terminal plugs 21, cord bushings and switch elements as in Figs. 1 to 6, except that the cord bushings 23, 24, 27 are below the level of its switch contact surface, and that the bracket support 35 for the amplifier unit is eliminated, so that the upper surface of the bottom wall 31 provides a flat surface for guiding the enlarged switch plate 83 to which the battery terminal plugs 21, 22 are clamped. The two bushings 61, 62 extending from the contact spring arms 55, 56, 25 respectively, and holding clamped to the switch plate 83 the downwardly extending battery plugs 21, 22, have upwardly extending terminal sleeves 81, 82 so that a self-contained standard microphone amplifier unit may be detachably mounted 30 on the switch plate 83 by plugging the battery terminals 21', 22' of such amplifier unit into the terminal sleeves 81, 82 of the switch plate 83. A cover plate 84 having holes for the terminal sleeves 81, 82 is secured, as by screws 85, to the upper surface of the switch plate 83, and provides 35 a seat for the base of the amplifier unit 80.

The switch bottom wall 31 is also provided with a cord extension having two leads 25, 28 which are connected with a two-prong plug to the cord 45 terminal bushings 24, 27 of the standard amplifier unit 80 so as to complete circuit connections from its winding 14 and microphone 15 to the switch contacts 44, 45 in a way analogous to the similar connections established in the arrangement of Fig. 6.

The principles of the invention explained in connection with specific exemplifications thereof will suggest to those skilled in the art many other applications and modifications of the same. It is accordingly desired that the appended claims be construed broadly, and that they shall not be limited to the specific details shown and described in connection with exemplifications thereof.

I claim:

1. In a microphone amplifier unit for a hearing aid device comprising a transmitter microphone unit, a receiver unit, a battery unit and cord leads interconnecting the microphone unit, the receiver unit and the amplifier unit: a mounting member having battery terminals for interconnecting said amplifier unit to said battery unit; a supporting member for said amplifier unit movably mounted on said mounting member for movement between two positions; switch means having contact elements secured to said mounting member and contact elements secured to said supporting member and arranged to establish two different sets of circuit connections in said 60 two positions of said supporting member; an am-

plifier microphone; amplifier windings for actuating said amplifier microphone; cord lead terminals carried by said supporting member and interconnected to the contact elements of said supporting member; the contact elements of said switching means being so arranged and correlated, and the contact elements of said mounting member being so interconnected with said battery terminals that—in one position of said supporting member said switch means establish in conjunction with said cord leads an input circuit interconnecting said battery unit in series with said amplifier windings and said microphone unit, and an output circuit interconnecting said battery unit in series with said amplifier microphone and said receiver unit for supplying to said receiver unit amplified output currents corresponding to input currents in said input circuit,—and that in the other position of said supporting member said switch means establish in conjunction with said cord leads a circuit connecting said microphone unit and said receiver unit directly in series with said battery unit; said mounting member and said supporting member having substantially parallel facing surfaces for guiding said supporting member from one position to the other position.

2. In a microphone amplifier unit for a hearing aid device comprising a transmitter microphone unit, a receiver unit, a battery unit and cord leads interconnecting the microphone unit, the receiver unit and the amplifier unit; a mounting member having battery terminals for interconnecting said amplifier unit to said battery unit; a supporting member for said amplifier unit movably mounted on said mounting member for movement between two positions; switch means having contact elements secured to said mounting member and contact elements secured to said supporting member and arranged to establish two different sets of circuit connections in said two positions of said supporting member; an amplifier microphone; amplifier windings for actuating said amplifier microphone; cord lead terminals carried by said supporting member and interconnected to the contact elements of said supporting member; the contact elements of said switching means being so arranged and correlated, and the contact elements of said mounting member being so interconnected with said battery terminals that—in one position of said supporting member said switch means establish in conjunction with said cord leads an input circuit interconnecting said battery unit in series with said amplifier windings and said microphone unit, and an output circuit interconnecting said battery unit in series with said amplifier microphone and said receiver unit for supplying to said receiver unit amplified output currents corresponding to input currents in said input circuit,—and that in the other position of said supporting member said switch means establish in conjunction with said cord leads a circuit connecting said microphone unit and said receiver unit directly in series with said battery unit; said mounting member and said supporting member having substantially parallel facing surfaces for guiding said supporting member from one position to the other position; said battery terminals projecting outwardly from said mounting member and being arranged for slidably engagement with a part of said battery unit so as to form therewith a structure supporting said amplifier unit.

3. In a microphone amplifier unit for a hear-

ing aid device comprising a transmitter microphone unit, a receiver unit, a battery unit and cord leads interconnecting the microphone unit, the receiver unit and the amplifier unit; a mounting member having battery terminals for interconnecting said amplifier unit to said battery unit; a supporting member for said amplifier unit movably mounted on said mounting member for movement between two positions; switch means having contact elements secured to said mounting member and contact elements secured to said supporting member and arranged to establish two different sets of circuit connections in said two positions of said supporting member; an amplifier microphone; amplifier windings for actuating said amplifier microphone; cord lead terminals carried by said supporting member and interconnected to the contact elements of said supporting member; the contact elements of said switching means being so arranged and correlated, and the contact elements of said mounting member being so interconnected with said battery terminals that—in one position of said supporting member said switch means establish in conjunction with said cord leads an input circuit interconnecting said battery unit in series with said amplifier windings and said microphone unit, and an output circuit interconnecting said battery unit in series with said amplifier microphone and said receiver unit for supplying to said receiver unit amplified output currents corresponding to input currents in said input circuit,—and that in the other position of said supporting member said switch means establish in conjunction with said cord leads a circuit connecting said microphone unit and said receiver unit directly in series with said battery unit; said mounting member and said supporting member having substantially parallel facing surfaces for guiding said supporting member from one position to the other position; said mounting member and said supporting member being mechanically joined and being arranged to constitute with said switching means a self-supporting unit separable from said amplifier unit.

4. In a microphone amplifier unit for a hearing aid device comprising a transmitter microphone unit, a receiver unit, a battery unit and cord leads interconnecting the microphone unit, the receiver unit and the amplifier unit; a mounting member having battery terminals for interconnecting said amplifier unit to said battery unit; a supporting member for said amplifier unit movably mounted on said mounting member for movement between two positions; switch means having contact elements secured to said mounting member and contact elements secured to said supporting member and arranged to establish two different sets of circuit connections in said two positions of said supporting member; an amplifier microphone; amplifier windings for actuating said amplifier microphone; cord lead terminals carried by said supporting member and interconnected to the contact elements of said supporting member; the contact elements of said switching means being so arranged and correlated, and the contact elements of said mounting member being so interconnected with said battery terminals that—in one position of said supporting member said switch means establish in conjunction with said cord leads an input circuit interconnecting said battery unit in series with said amplifier windings and said microphone unit, and an output circuit interconnecting said battery unit in series with said amplifier microphone and said receiver unit for supplying to said receiver unit amplified output currents corresponding to input currents in said input circuit,—and that in the other position of said supporting member said switch means establish in conjunction with said cord leads a circuit connecting said microphone unit and said receiver unit directly in series with said battery unit; said mounting member and said supporting member having substantially parallel facing surfaces for guiding said supporting member from one position to the other position; said mounting member and said supporting member being mechanically joined and being arranged to constitute with said switching means a self-supporting unit separable from said amplifier unit.

unit for supplying to said receiver unit amplified output currents corresponding to input currents in said input circuit,—and that in the other position of said supporting member said switch means establish in conjunction with said cord leads a circuit connecting said microphone unit and said receiver unit directly in series with said battery unit; said mounting member and said supporting member having substantially parallel facing surfaces for guiding said supporting member from one position to the other position; said battery terminals projecting outwardly from said mounting member and being arranged for slideable engagement with a part of said battery unit so as to form therewith a structure supporting said amplifier unit; said mounting member and said supporting member being mechanically joined and being arranged to constitute with said switching means a self-supporting unit separable from said amplifier unit.

5. In a microphone amplifier unit for a hearing aid device comprising a transmitter microphone unit, a receiver unit, a battery unit and cord leads interconnecting the microphone unit, the receiver unit and the amplifier unit: a mounting member having battery terminals for interconnecting said amplifier unit to said battery unit; a housing member for said amplifier unit movably mounted on said mounting member for movement between two positions; switch means having contact elements secured to said mounting member and contact elements secured to said housing member and arranged to establish two different sets of circuit connections in said two positions of said housing member; an amplifier microphone; amplifier windings for actuating said amplifier microphone; cord lead terminals carried by said housing member and interconnected to the contact elements of said housing member; the contact elements of said switching means being so arranged and correlated, and the contact elements of said mounting member being so interconnected with said battery terminals that—in one position of said housing member said switch means establish in conjunction with said cord leads an input circuit interconnecting said battery unit in series with said amplifier windings and said microphone unit, and an output circuit interconnecting said battery unit in series with said amplifier microphone and said receiver unit for supplying to said receiver unit amplified output currents corresponding to input currents in said input circuit,—and that in the other position of said housing member said switch means establish in conjunction with said cord leads a circuit connecting said microphone unit and said receiver

unit directly in series with said battery unit; said mounting member and said housing member having substantially parallel facing surfaces for guiding said housing member from one position to the other position; said housing member forming part of a housing enclosing said amplifier microphone and said amplifier windings.

6. In a microphone amplifier unit for a hearing aid device comprising a transmitter microphone unit, a receiver unit, a battery unit and cord leads interconnecting the microphone unit, the receiver unit and the amplifier unit: a mounting member having battery terminals for interconnecting said amplifier unit to said battery unit; a housing member for said amplifier unit movably mounted on said mounting member for movement between two positions; switch means having contact elements secured to said mounting member and contact elements secured to said housing member and arranged to establish two different sets of circuit connections in said two positions of said housing member; an amplifier microphone; amplifier windings for actuating said amplifier microphone; cord lead terminals carried by said housing member and interconnected to the contact elements of said housing member; the contact elements of said switching means being so arranged and correlated, and the contact elements of said mounting member being so interconnected with said battery terminals that—in one position of said housing member said switch means establish in conjunction with said cord leads an input circuit interconnecting said battery unit in series with said amplifier windings and said microphone unit, and an output circuit interconnecting said battery unit in series with said amplifier microphone and said receiver unit for supplying to said receiver unit amplified output currents corresponding to input currents in said input circuit,—and that in the other position of said housing member said switch means establish in conjunction with said cord leads a circuit connecting said microphone unit and said receiver unit directly in series with said battery unit; said mounting member and said housing member having substantially parallel facing surfaces for guiding said housing member from one position to the other position; said battery terminals projecting outwardly from said mounting member and being arranged for slideable engagement with a part of said battery unit so as to form therewith a structure supporting said amplifier unit; said housing member forming part of a housing enclosing said amplifier microphone and said amplifier windings.

ALFRED J. MASTROPOLE.
